UNITED STATES PATENT OFFICE.

SAMUEL J. JOHNSTON, OF LEESBURG, VIRGINIA.

COMBINATION-TOOL.

SPECIFICATION forming part of Letters Patent No. 601,302, dated March 29, 1898.

Application filed April 28, 1896. Renewed September 7, 1897. Serial No. 650,843. (No model.)

To all whom it may concern:

Be it known that I, SAMUEL J. JOHNSTON, a citizen of the United States, residing at Leesburg, in the county of Loudoun and State of Virginia, have invented a new and useful Combination-Tool, of which the following is a specification.

My invention relates to combination-tools, and particularly to an improvement upon the tool shown and described in Letters Patent No. 530,419, granted to me December 4, 1894.

The object in view is to construct a tool of adjustable or interchangeable parts or members which may be arranged to adapt the same to perform various functions, and particularly to improve the construction of the device in the matter of the screw-driving member, the bit and wrench-brace, the bench-vise, including the means for its attachment to a bench, the wrench-head, and the coöperating parts.

Further objects and advantages of this invention will appear in the following description, and the novel features thereof will be particularly pointed out in the appended claims.

In the drawings, Figure 1 is a view of a tool constructed in accordance with my invention arranged for use as a bit and wrench-brace. Fig. 2 is a sectional view of the same. Fig. 3 is a perspective view of the tool arranged for use as a straight wrench and as a long screw-driver. Fig. 4 shows the short-handled screw-driver detached. Fig. 5 shows the tool arranged for use as an S-wrench. Fig. 6 is a view of the tool arranged for use as a glass-cutter and can-opener. Fig. 7 is a transverse section on the line 7-7 of Fig. 1 to show the latch for securing the handle against rotation. Fig. 8 is a perspective view of the device arranged for use as a bench-vise.

Similar numerals of reference indicate corresponding parts in all the figures of the drawings.

1 designates a cross-sectionally angular shank, terminating at its outer end in a preferably integral fixed jaw 2, forming one member of the wrench-head, and fitted to slide upon said shank is the movable or adjustable jaw 3, actuated by a feed-screw 4, swiveled in the cross-head 5 at the inner end of the shank. In order to adapt the wrench for right and

left hand use, the wrench-head is extended in opposite directions from the shank to form the main and auxiliary fixed jaws 2^a and 2^b 55 and the main and auxiliary movable or adjustable jaws 3^a and 3^b. The inner surfaces or faces of the main fixed and movable jaws are channeled, as shown at 6, to receive a bit 7, as shown in dotted lines in Fig. 2. 60

The feed-screw 4 terminates at its inner end in a thumb-head 8, having arms or ears 8^a and 8^b, which are respectively constructed to form a glass-cutter and a can-opening blade. For this purpose a diamond-wheel 9 65 is set in a bifurcation in the ear 8^a, and said ear is provided with a breaking-notch 10 to receive the edge of the glass after the scoring thereof by the wheel. The outer edge of the ear 8^b is reduced to form a blade, and the 70 shoulders 11 of the thumb-head form rests to bear upon the top of the can or other article to be opened. Inasmuch as these shoulders are arranged upon both sides of the plane of the can-opening blade or ear 8^b, it is obvious 75 that the can-opener is adapted for either right or left hand use.

The cross-head 5 is provided with perpendicularly-disposed screw-studs 12 and 13, the former of which is perpendicular to the plane 80 of the cross-head, and hence parallel with the shank of the tool, and the latter is formed as an extension of the cross-head, and hence is perpendicular to the shank, the end of the cross-head contiguous to the stud 13 being 85 broadened to form a securing ear or rest 14, provided with perforations 15, through which fastening screws or nails may be driven, as indicated in Fig. 8, to fasten the portion of the tool already described to a bench 16, and thus adapt it for use as a bench-vise. The extremities of the auxiliary portions 2^a and 3^a of the jaws form a rest to coöperate with the rest 14 to steady the apparatus when used as a vise. 95

The handle portion or member 17 of the tool consists of a tubular core or body portion 18, terminating at its inner end in a handhold consisting of a circumferentially-milled disk 19, and terminating at its outer end in a screw-driver bit 20, which is thus rigid with the body portion of the handle, and a grip 21, which is loosely mounted for free rotary movement upon said body portion, said handhold

and bit respectively projecting beyond the contiguous extremities of the grip. The inner end of the bore of the tubular body portion of the handle is threaded to form a socket 5 for the reception of either of the threaded studs 12 and 13 on the cross-head of the tool, and when the handle is attached to the cross-head by means of the stud 13, as shown in Fig. 3, the tool is adapted for use as a straight-handled wrench or by reversal as a long-handled screw-driver, in which case the wrench-head forms a grip. In order to adapt this wrench-head to perform its function as a convenient grip in manipulating the long-handled screw-driver, the exposed or upper and lower sides, respectively, of the fixed and movable jaws are rounded, as shown. The movable jaw is adapted to be adjusted outwardly to the limit of its movement when the 15 device is to be used as a long-handled screw-driver. When the tool-handle is detached, as shown in Fig. 4, it forms a short-handled screw-driver suitable for light work or for use under conditions precluding the employment 20 of the long-handled tool. (Illustrated in Fig. 3.) The milling of the periphery of the disk at the inner end of the body portion of the handle provides the proper grip by which the bit may be turned, and inasmuch as the 25 bit is integral with the body portion of the handle it may be made of sufficient strength to resist any strain to which it may be subjected.

When the socket in the inner end of the 30 handle is engaged with the stud 12, as shown in Fig. 5, the device is adapted for use as an S-wrench—a desirable form of the tool for certain classes of work in connection with which the ordinary or straight-handled form 35 of wrench shown in Fig. 3 is inoperative. When the handle is arranged at right angles to the shank by its engagement with the stud 12, it is desirable to secure the handle-body portion or spindle from rotation, and the 40 means which I employ for accomplishing this object consists of a latch having a spring-actuated bolt 22, mounted in an open-ended sheath or guide 23, preferably integral with the cross-head and parallel with the stud 12, for engaging a perforation 24 in the peripherally-milled disk at the inner end of the handle. This bolt is reduced at one end, as 45 shown at 25, to form a shoulder 26, between which and the inner end of the guide is arranged a coiled spring 27, the parts being held in said position by the permanent attachment of a thumb-hold 28 to the inner extremity of the bolt, said thumb-hold serving to limit the extension of the bolt under the 50 tension of its actuating-spring.

In Figs. 1 and 2 I have shown the tool arranged for use as a bit and wrench-brace, in which case the wrench-head and connected parts and the handle are arranged, as shown 55 in Fig. 5, with the handle in engagement with the stud 12 or perpendicular to the shank, and applied to the outer end of the handle is

a brace-arm 29, provided with a cross-sectionally angular terminal socket 30, which is adapted to fit upon and form a sheath for the screw-driver bit at the outer end of the handle. Thus the screw-driver bit performs, in addition to its usual function, that of a stud for the attachment of the brace-arm, and by tapering the screw-driver bit the brace-arm 75 may be driven to place thereon to form a sufficiently firm attachment of the parts.

From the above description it will be seen that the screw-driver bit is permanently attached to the body portion of the handle and 80 is adapted to perform its function as a screw-driver when exposed by the removal of the brace-arm and either detached from the shank or attached parallel therewith, as shown, respectively, in Figs. 4 and 3. When the handle is detached from the shank, the latter may be attached to a bench for use as a vise or may be reversed to perform its function as a glass-cutter or can-opener. The rest, which is formed upon the extremity of the cross-head and parallel with the shank to bear upon the bench, is located at the same distance from the shank as the extremity of that portion of the wrench-head which is upon the same side of the shank, or that portion of the 90 wrench-head formed by the auxiliary fixed and movable jaws. Thus when the device is arranged for use as a bench-vise the face of the rest and the extremity of the short end of the wrench-head bear upon the surface of 100 the bench, the additional bearing formed by the short arm of the wrench-head serving to steady the device and relieve the securing means of strain.

The advantage of the manner of mounting 105 the latch resides in the fact that the spring and contiguous portion of the sliding bolt are wholly concealed within the sheath and are thereby protected from moisture to prevent accumulations of dust and rust from 110 rendering the latch inoperative.

Some of the uses of the tool embodying my 115 invention have been above described; but it is obvious that its parts or members are capable of numerous relative arrangements and are adapted to perform functions which it is unnecessary to explain herein in detail; and it will be understood, furthermore, that various changes in the form, proportion, and the 120 minor details of construction may be resorted to without departing from the spirit or sacrificing any of the advantages of my invention.

Having described my invention, what I claim is—

1. In a tool of the class described, the combination of a shank carrying fixed and adjustable jaws, a detachable handle having a core or body portion upon which is mounted a revoluble grip, said core or body portion terminating at one end, beyond the contiguous extremity of the revoluble grip, in a hand-hold, and terminating at the other end in a cross-sectionally angular screw-driver bit which projects beyond the contiguous ex-

tremity of said revoluble grip, whereby the handle may be independently used as a short screw-driver, means for securing the handle to the shank either parallel with or perpendicular thereto, and a brace-arm provided with a terminal cross-sectionally angular socket to receive the screw-driver bit, said bit constituting means for securing the brace-arm to the handle, and being concealed by the said socket, substantially as specified.

2. In a tool of the class described, a shank terminating at opposite ends in a fixed jaw and a cross-head, a movable jaw mounted upon the shank, and adjusting devices for the movable jaw, said fixed and movable jaws being extended in opposite directions from the plane of the shank to form a double wrench-head, and the cross-head terminating at one end in a perforated rest which is arranged with its face at the same distance from the shank as the extremity of that portion of the wrench-head which is arranged upon the same side of the shank, substantially as specified.

25 3. In a tool of the class described, the combination of a shank terminating at one end in a fixed jaw which extends in opposite di-

rections from the shank to form main and auxiliary portions, and terminating at the other end in a cross-head, a movable jaw mounted upon the shank, means for adjusting the movable jaw, and a rest carried by the cross-head with its face parallel with the shank and in the plane of the extremity of the auxiliary portion of the fixed jaw, said rest being provided with means for attachment to a bench, substantially as specified.

4. In a tool of the class described, the combination of a shank terminating at one end in a fixed jaw and at the other end in a cross-head, a movable jaw mounted to slide upon the shank, means for adjusting the movable jaw, and spaced rests arranged at opposite ends of and upon the same side of the shank to adapt the tool for attachment to a bench, substantially as specified.

In testimony that I claim the foregoing as my own I have hereto affixed my signature in the presence of two witnesses.

SAMUEL J. JOHNSTON.
